UNITED STATES PATENT OFFICE.

DENNIS J. ALLEN, OF BINGHAMTON, NEW YORK.

RAILWAY SIGNAL DEVICE.

1,388,787.

Specification of Letters Patent. Patented Aug. 23, 1921.

Application filed September 7, 1920. Serial No. 408,429.

To all whom it may concern:

Be it known that I, DENNIS J. ALLEN, a citizen of the United States, residing at Binghamton, in the county of Broome and State of New York, have invented certain new and useful Improvements in Railway Signal Devices, of which the following is a specification.

This invention relates to signal devices, 10 more particularly to apparatus employed in railway operations, and has for one of its objects to provide a device of this character whereby the engineer in the cab of a locomotive is warned of the approach to a 15 semaphore, and signals both aural and visible transmitted to him, the signals, preferably being duplicates of those imparted by the semaphore.

With these and other objects in view, the 20 invention consists in certain novel features of construction as hereinafter shown and described and then specifically pointed out in the claim, and in the drawings illustrative of the preferred embodiment of the invention.

Figure 1 is a diagrammatic view of a section of railway track and a plurality of semaphores, with the portions of the improved signaling associated therewith,

30 Fig. 2 is a diagrammatic detail of the portions of the apparatus associated with the locomotive and the engineer's cab, together with one of the semaphores alongside the track.

35 Fig. 3 is an enlarged face view of the casing containing the portion of the mechanism in the engineer's cab.

The track rails are indicated at 10 and two 40 semaphore standards at 11, the latter being located at the terminals of a "block," each semaphore indicating the beginning and ending of each "block."

The standards 11 carry the usual swinging signal imparting arms 12 and 13.

45 Located adjacent the rails 10, preferably between them, and also adjacent each semaphore standard, are contact members 14, which for illustration are shown formed of sections of railway rails.

50 Other contacts 15 are also located intermediate the semaphore standards, as shown in Fig. 1.

Attached to the locomotive are other contacts adapted to engage the contacts 14 and 55 15 as the locomotive passes over the track.

The contacts carried by the locomotive may be of any suitable form, but for illustration are shown in the form of disks 16 carried by one of the axles 17 of the forward truck and insulated therefrom, as shown at 18 in Fig. 2.

The frame 19 of the truck carries "brushes" 20 in constant contact with the disks 16, to which the conductor wires are connected.

Located in the engineer's cab is a casing 21 carrying the operating devices whereby the positions of the main semaphore arms are duplicated in miniature on the casing 10, so that the engineer will have before his eyes a set of the arms set in exactly the same position as those on the main semaphores alongside the track outside.

The mechanism in the casing 21 comprises coacting shafts 22 and 23 carrying arms 24 and 25 duplicates in miniature of the main arms 12 and 13, and externally of the face of the casing.

Attached respectively to the shafts 22 and 23 within the casing are pinions 26 and 27, and pivoted at 28 and 29 are arms 30 and 31 each having a gear segment at one end engaging respectively with the pinions 26 and 27.

Located within the casing 21 are electro-magnets 32 and 33, and pivoted at 34 and 35 are armature levers 36 and 37 within the influence of the magnets. The armature lever 36 is coupled at 38 to the segment carrying arm 30, while the armature lever 37 is coupled at 39 to the segment carrying arm 31.

By this arrangement when the magnets 32 and 33 are energized, the miniature semaphore arms 24 and 25 will be moved into signal imparting position. Supported in a frame 40 is a bell or gong sounding mechanism of approved construction, and represented as a whole at 41. The sounding mechanism is adapted to be controlled by an electromagnet 42 arranged to operate a releasing lever 43.

The magnet 32 and the sounding mechanism are in electrical connection by wires 44 through a suitable source of power, for instance a battery represented conventionally at 45.

The magnet 42 is in electrical connection with frame 19 and one of the brushes 20 by conductor wires 46.

The magnet 33 is in electrical connection with the frame 19 of the truck and the other

brush 20 by conductor wire 47, with a call bell or "buzzer," of suitable construction and indicated at 48 in the circuit of the conductor wire 47.

5 Located in the paths of the arms 12 and 13, are circuit closing devices 49 and 50, the latter being connected by wires 51 with the line rails 10 and contact rails 14 and 15 and through a battery 52, or other source of 10 power.

The tracks 10 are provided at suitable intervals with insulated rail joints 53 which separate the track into blocks.

15 The mechanism in the casing 21 is spring controlled, and a hand 54 is attached to the mechanism externally of the casing, to indicate the condition of the spring, to notify the engineer when it requires rewinding.

20 By this arrangement, when the locomotive enters a "block," the miniature semaphores 24 will be disposed in the same relative position as those on the post or standard outside. For instance if the upper arm 12 is elevated to indicate "caution," the arm 25 in rising to horizontal or caution position, will engage the contact 49 and close the circuit through the wire 51—cause the corresponding miniature arm 24 in the engine cab to assume the same position, and at the same 30 time sound the bell or buzzer 48, thus informing the engineer of condition of the main semaphore.

35 Then on the other hand if the lower arm 13 or the one to indicate "danger," is actuated, the contact 50 will be engaged, and the corresponding miniature arm 25 to be correspondingly actuated, as will be obvious.

40 The same operations will take place when the locomotive passes over the intermediate contacts 15, so that the engineer can be kept posted as to the condition of the semaphores

when in an intermediate position in the "block."

45 The intermediate contact rails may be located at as many points in each "block" as required, depending on circumstances, or the contour of the line.

50 The preferred embodiment of the invention is disclosed in the drawings and set forth in the specification, but it will be understood that any modifications within the scope of the claim may be made in the construction without departing from the principle of the invention or sacrificing any of 55 its advantages.

I claim:

60 In a signal apparatus, a semaphore device adjacent a railway line, electrical means for actuating the line semaphore device, a support on a moving train, a miniature semaphore mounted for oscillation within said support and carrying a gear pinion, an arm mounted for oscillation and carrying a gear segment engaging said gear pinion, an electromagnet for said arm, an armature swinging at one end adjacent said magnet, an extension from said armature and connected to said arm, an elongated electrical contact adjacent the railway line and in electrical connection with the line semaphore, an electric contact carried by the moving train in position to engage the elongated contact, and electric connections between said electric contacts and the electromagnet, whereby the 65 miniature semaphores are moved into the 70 same relative position as the line semaphore when the train contact engages the elongated contacts.

75 In testimony whereof, I affix my signature hereto.

DENNIS J. ALLEN.
